UNITED STATES PATENT OFFICE.

CHARLIE F. SIMPSON, OF MARTHA, OKLAHOMA.

COTTON GIN.

1,406,094.

Specification of Letters Patent.

Patented Feb. 7, 1922.

Application filed April 19, 1921. Serial No. 462,591.

To all whom it may concern:

Be it known that I, CHARLIE F. SIMPSON, a citizen of the United States, residing at Martha, in the county of Jackson and State 5 of Oklahoma, have invented new and useful Improvements in Cotton Gins, of which the following is a specification.

This invention relates to improvements in cotton gins and has especial relation to that 10 type of gin known as pneumatic gins, in which an air blast is utilized for removing the lint from the saws.

In gins of this type, the air blast, while removing the lint of the air blast and causing 15 the greater quantity thereof to pass out through the lint flue, also causes a quantity of lint to collect in the restricted end of the air duct adjacent to or just back of the nozzle, so that to insure the proper operation 20 of the gin, the air duct must be cleaned at intervals, which necessitates stopping the operation of the gin.

The present invention aims to eliminate this disadvantage by providing means for 25 cleaning or removing the accumulated lint from the air duct without interfering with the operation of the gin.

Other objects and advantages of the invention will appear as the following description 30 is read in connection with the accompanying drawings.

In the drawings:—

Figure 1 is a sectional view of a cotton gin 35 of the pneumatic type.

Figure 2 is a fragmentary sectional view on the line 2—2 of Figure 1.

Figure 3 is a detail view of the roller.

Referring in detail to the drawings, wherein like characters of reference denote 40 corresponding parts, the reference character 10 indicates one of the saws of a gin, 11 the lint flue and 12 the air duct, to which air is supplied from an air chamber 13. At the juncture of the lint flue and air duct, the gin 45 is arranged to provide a nozzle 14 so as to discharge a jet of air across a portion of each saw to remove the lint and carry it through the lint flue to the usual condenser.

The foregoing structure is that usually 50 found in pneumatic gins and its disadvantage resides in the fact that a portion of the lint removed from the saw teeth is caused by the air blast to accumulate in the re-

stricted part of the air duct and to interfere with the passage of air through this duct 55 and consequently interfere with the operation of the gin.

To overcome this, the present invention aims to provide means for removing this obstruction during the operation of the gin. 60 For this purpose there is provided a roller 16, which is mounted at each end upon trunnions 17, one of which has secured thereto an operating handle 18 which is located upon the outside of the gin casing and by 65 means of which the roller may be rotated as desired. The roller 16 is mounted within the machine so that its periphery will be spaced from but disposed concentrically to one wall of the air duct 12 and thus form a 70 section of the opposite wall of this duct. In addition there is provided an arcuate wall 19 having one edge located adjacent the periphery of the roller 16 and its opposite edge connected to the partition which 75 divides the air duct from the lint flue, so that a housing is formed which encloses substantially one-half of the roller. If desired this roller may have its periphery provided with grooves or serrations to more readily 80 take hold of the lint.

When an obstruction is formed in the duct, the roller may be rotated so as to carry the obstruction upward toward the nozzle 14, until it is forced by the saws over the 85 arcuate wall 19 into the lint flue 11, where it is carried to the condenser in the usual manner.

The invention is susceptible of various changes in its form, proportions and minor 90 details of construction and the right is herein reserved to make such changes as properly fall within the scope of the appended claim.

Having described the invention what is claimed is:

The combination with a cotton gin, of a longitudinally grooved roller rotatably mounted in the gin adjacent the air nozzle and having its periphery arranged to provide a portion of the air duct wall, and 100 means whereby the roller may be rotated to convey accumulated lint from the air duct to the lint flue.

In testimony whereof I affix my signature.

CHARLIE F. SIMPSON.
